UNITED STATES PATENT OFFICE.

HICKFORD MARSHALL AND SETH S. COOK, OF STAMFORD, CONNECTICUT, ASSIGNEES TO
JOHN BOSTWICK, JR., AND ELBERT WHITE.

ARRANGEMENT OF JACK-CHAIN MACHINERY.

Specification of Letters Patent No. 8,815, dated March 16, 1852.

To all whom it may concern:

Be it known that we, HICKFORD MARSHALL and SETH S. COOK, of Stamford, in the county of Fairfield and State of Connecticut, have invented certain new and useful Improvements in Machines for Making Jack or Pump Chain; and we do hereby declare that the following is a full, clear, and exact description of the same, reference being had to the accompanying drawings, forming part of this specification, in which—

Figure 1, is a plan or top view of the machine with a piece of wire inserted and the levers ready for turning the link. Fig. 2, is also a plan showing the wire with one eye of a link turned showing also the position to which the levers are moved for the purpose. Fig. 3, is a view of part of the 20 machine showing the manner in which two links are united.

Similar letters of reference indicate corresponding parts in each of the several figures.

A, represents the bed plate of the machine to which most of the working parts are attached; it is secured to a wooden block C, and one of its corners B, constituting a small horizontal table of the form of part of a circle, overhanging a slightly recessed 25 part D, of the face of the block.

E, is the mandrel around which the eyes of the links are turned or formed. It is secured in the small table B, at a distance from the center, and stands up a short distance above the surface. A notch or recess a, is formed in the plate at the back of the mandrel, extending also up the mandrel, being of suitable form and depth to receive one half of an eye of a link. F, is another 35 pin against which the wire rests while the links are being formed; it is secured in the plate A, at a convenient distance from E, and stands about the same height. A recess d, similar to a, and at right angles to it is 40 formed in the plate behind this pin E.

G, is a flat bar of metal hung on a fixed pivot b, above the plate A, and constituting a swinging jaw, it is provided with a tooth c, at its end, and is capable of swinging 45 across the plate A, so as to bring the point of its tooth c, about midway between the mandrel E, and pin F.

H, is a lever, hung on a fulcrum pin e,

above the plate A, and having its shorter arm formed as a cam. The jaw G, is always thrown back against this cam by a spring I, being confined to the plate A, so as to prevent its rising, by a guide bar J, which is secured above it.

K, is the turning lever hung below the small table B, on a pin i, in the center of the said table, (represented by a dotted circle in all the figures.) It carries on its upper side the turning pin f, which is nearly close to the edge of the table, being just allowed to clear it.

g, represents the piece of wire of which a link is to be formed, and h, in Fig. 3, a link to which another is about to be joined.

The machine is put in operation in the following manner: The levers H, and K, are both governed by hand, and can be moved to the position shown in Fig. 1 to that shown in Fig. 2, and vice versa. While they are in the first named position, the wire, 75 which is cut to the required lengths to form a link, is laid on the plate A across the small table B, with one end slightly overhanging the outside edge of the table. The long arm of the lever H, is then thrown back to the 80 position shown in Fig. 2, and the cam end drives the nipping jaw G, forward and causes the point of its tooth to press on the wire and force it against the pin F, and mandrel E, giving it a slight bend, which 85 assists in forming the eye, and then holding it secure while the eye is turned. The lever K, is then moved from the position shown in Fig. 1, to that shown in Fig. 2, and the pin f, moving around the rim of the table 90 carries around the end of the wire and bends it around the mandrel E, and thus forms one eye. The wire is then taken off the mandrel and its ends reversed in the machine, see g, (Fig. 3,) the eye first formed 95 being placed edgewise upward and one side put in the recess d, to bring the straight part flat on the plate ready for turning the other eye at a right angle to it, by a similar movement of the parts. To make the chain, 100 the link last formed is placed with one eye flat on the plate, and one turned edgewise upward in the recess a. (See h, Fig. 3.) The link to be joined having one eye formed is put in the machine like g, Fig. 3, and the 105 straight parts to be turned put through the

forward eye of the link *h*, and when it is turned to form the eye, it incloses the eye of *h*.

What we claim as our invention and desire to secure by Letters Patent, is—

The arrangement on the bedplate *A* of the nipping jaw *G*, the mandrel *E*, and pin *F*, with the turning lever *K* (furnished with

pin *f*), moving under the table *B*, in the manner and for the purpose substantially as set forth and shown.

HICKFORD MARSHALL.
SETH S. COOK.
